REFRIGERATION BY DIRECT VAPOR CONDENSATION

James B. Maher and James Mair, Chicago, Ill., assignors to Chicago Bridge & Iron Company, Chicago, Ill.
Filed Dec. 23, 1960, Ser. No. 73,075
5 Claims. (Cl. 62—54)

This invention relates to the refrigerated storage of a liquefied normally gaseous product. It more particularly relates to controlling the vapor pressure of the stored liquid product by direct vapor condensation.

It is well known in the art that for liquids whose vapor pressure is greater than one atmosphere at normal atmospheric temperature, a refrigerated tank provides an efficient storage facility. Insulation of the storage tank is necessary and refrigeration equipment must be provided to remove the heat introduced by (a) heat leak into the tank from the surrounding atmosphere and (b) heat introduced as sensible heat in the filling stream entering the tank.

When the stored liquid product is relatively pure and substantially free of constituents having a lower boiling point than the stored product, the refrigeration can be effected by withdrawing vaporous product effluent from the tank by a compressor, compressing it to a point at which it may be condensed by cooling with ambient air or available water, and returning the condensed liquid to the storage tank wherein it is flash-vaporized at storage conditions. The refrigeration effect produced by this conventional vapor compression refrigeration system maintains the stored product at design temperature. This method is also referred to as "self-refrigeration" or "open cycle refrigeration."

If, however, the stored liquid product contains a 0.5% to 5.0% or more of constituents having a lower boiling point than the stored liquid, these constituents will appear as non-condensable gases at the temperature and pressure prevailing in the condenser, eventually raising the back-pressure on the compressor until the refrigeration system becomes inoperative. In such cases, and especially when the stored liquid product is a mixture of components having different boiling points, it is necessary to resort to "closed-cycle" refrigeration.

In closed-cycle refrigeration the stored liquid is withdrawn from the tank, cooled in a heat exchanger, and returned to the tank. Experience has shown that it is very difficult to control the vapor pressure in the tank by this method, because:

(a) There are zones of varying temperature throughout the storage tank;

(b) The cooling and condensing effect of the liquid surface on the vapor in the vapor space is slow and delayed;

(c) Even if the cold returned liquid is sprayed into the vapor space, low contact time and limited dispersion affect the rate of vapor condensation.

In accordance with this invention, there is provided an apparatus and a method employing a closed-cycle refrigeration system whereby the tank pressure can be controlled without heating or further vaporizing the product by the recirculated stored liquid thereby limiting the release of vapor not condensable in the main refrigeration condenser.

Referring to the drawings:

FIGURE 1 is a schematic flow diagram of a refrigeration system employed in the instant invention.

2

FIGURE 2 is a schematic cross-sectional elevation view of a direct contact condenser used for effecting an intimate contact between the recycled cooled product and the vaporous effluent from the storage system.

5 FIGURE 3 is an enlarged cross-sectional view taken along line 3—3 of FIGURE 2 to illustrate the mounting arrangement for the condenser vapor tube.

In FIGURE 1, there is diagrammatically illustrated an illustrative embodiment of the refrigeration storage system which comprises a conventional flat-bottom insulated tank 10, which is used to store the product. Because tank 10 is not completely filled with liquid product there exists a vapor space V above the liquid. To effect the refrigeration of the stored product, there is also provided a refrigeration system which comprises a conventional refrigerator 11 which cools a heat exchanger fluid which circulates through lines 12 and 13 to heat exchanger 14. In the exchanger 14 the liquid L is sub-cooled after being drawn from the tank 10 through line 15 and 16 by means of pump 17 which circulates liquid L from the heat exchanger 14 by way of line 18 to the direct condenser 20, from which it returns to the storage tank by gravity.

Referring to FIGURE 2, there is shown a direct contact condenser 20, connected to the top of tank 10 by means of flanged nozzle 19. As illustrated, the condenser 20 comprises a chamber 21 in which is arranged a series of baffle trays 22 and 23 and a diffuser baffle 24. Baffles 22 are annular discs having a central opening 25. The discs are attached to the wall of chamber 21. Baffle trays 23 having a smaller outer diameter than the internal diameter of chamber 21 are mounted on a vapor pipe 26 which is coaxially suspended within chamber 21 by means of suitable spider arms 27 which radially extend from baffle trays 23 and are fastened to the wall of chamber 21. Diffuser baffle 24 which serves to prevent the flow of circulating liquid L directly in vapor pipe 26, and distribute the liquid over the interior of the chamber is suspended from the domed chamber end closure 28 by means of hangers 29. Vapor pipe 26 which extends into the vapor space V of tank 10 is provided with perpendicularly extending vapor withdrawal side arms 30 and 31 which improves the vapor gathering efficiency of the vapor withdrawal means. A purge line 32 is used to remove any non-condensables which accumulates from time to time in the condenser 20 and pass them, for example, to a suitable flare, not shown.

In operation, the sub-cooled circulating liquid L discharging from line 15 enters the condenser 20 wherein it is distributed by baffle 24 and cascades over the series of 50 alternating baffle trays 22 and 23 which are alternately arranged in the condenser chamber 21 to provide maximum contact time and surface between the liquid and vapor. The T-shaped vapor withdrawal means withdraws product vapor including non-condensables from the vapor space to replace vapor condensed in the condenser 20. Most of the low boiling point constituents or non-condensables present in the vapor space are also condensed or are carried by entrainment back to the vapor space through the annulus between the vapor pipe 26 and the mounting nozzle 19 on tank 10. The small amount of non-condensables which do not return to the storage tank accumulate in the dome of condenser 20 from whence they can be removed from time to time through line 32.

65 In condenser 20 the baffle trays 22 depend inwardly from the side wall of condenser 20 and the baffle trays 23 are supported by the vapor inlet pipe 26, which also

conducts vapor gathered from the vapor space to the top of the condenser 20. With this arrangement, only one mounting nozzle 19 functioning as vapor inlet, condensate outlet, and vent gas outlet is required.

In an arrangement such as shown in FIGURE 1, a conventional, insulated, double-wall, flat bottom cylindrical 50-barrel storage tank storing liquid n-butane, containing 2% of propane as non-condensable, at 30° F. and 0.5 p.s.i.g. can be used. The required inner storage vessel is 80 feet in diameter and 56 feet high. The tank is covered with 5 inches of Foamglas or other suitable insulating material. Accordingly the refrigeration system must compensate for a warming up of the liquid, L, of 120,000 B.t.u.'s per hour. In this example, 35 gallons per minute, or 10,300 pounds per hour, of the n-butane are withdrawn by a suitable pump and cooled in a heat exchanger. In the heat exchanger the temperature of the n-butane is cooled from the 30° F. storage temperature to 10° F. by conventional, indirect, heat-exchange, refrigeration apparatus. The sub-cooled n-butane is circulated into a direct contact cascade condenser of the type illustrated in FIGURE 2 which is mounted atop the storage tank from which it discharges into the vapor space. The recirculated n-butane condenses 560 pounds per hour of the warmer vapor in the condenser while reaching an equilibrium temperature of 25° F. Both the recirculated n-butane and the condensed vapor re-enter the tank, and additionally cool the stored n-butane until the resulting equilibrium temperature of 30° F. storage temperature is reached by the returning liquid. The total refrigeration effect of the continuous recirculation system is 120,000 B.t.u.'s per hour, as was required.

This invention offers the following advantages:

(1) Pressure control is effected by manipulating the product in the vapor phase insuring fast, accurate response to signals from a controller used to control the flow of circulating refrigerated stored product.

(2) At no point in the product cycle is the product exposed to a higher temperature.

(3) Product is not vaporized and condensed in the refrigeration cycle, the only vaporization is that due to heat leak and this vapor is immediately condensed by sub-cooled product.

(4) Product vapor is condensed at storage temperature and pressure by intimate contact with sub-cooled product liquid.

(5) The condenser has no tubes or heat transfer surface which could become fouled and require maintenance.

(6) The design of the concentric vapor inlet to the condenser enables the condenser to bring in a continuous stream of vapor from the storage tank to be purged of lower boiling constituents by entrainment through the annular space around the vapor pipe.

(7) The device is simple in design, requires no maintenance, and mounts directly on the storage vessel.

While some storage facilities include tanks in which the product is held at close to atmospheric pressure, others are operated at temperatures which correspond to pressures above or below atmospheric. Being completely sealed, this invention is applicable to any refrigeration storage system at any pressure.

The instant invention has especial application in the refrigerated storage at temperatures within the range of about 10° to 40° F. of liquefied materials such as C₁-C₅ hydrocarbons such as ethylene, butadiene, iso-butane, chlorine, ethyl chloride, vinyl chloride, ethylene oxide, ammonia, etc., containing more than about 0.5% non-condensables. Other products and other storage conditions, however, can be used. It can be employed in storage facilities where 10,000 to 6,000,000 gallons per tank of liquid material are stored. Conventional materials of construction and equipment are utilized in assembling the storage system of this invention. The refrigeration system employed to cool the recirculated liquid material should have sufficient capacity to sub-cool it at least 20° F.

below storage conditions. Because there is no compression cycle, the non-condensates do not interfere with the operation of this refrigeration system as they do in conventional refrigeration systems.

5 The liquid vapor contact apparatus employed to condense the vapor withdrawn from the vapor space should have sufficient contact area provided to condense substantially all of the vapor withdrawn in the condenser chamber. Other types of cascade contact apparatus as well as 10 other liquid-vapor contact equipment such as bubble towers, etc., can be used. Such modifications and variations will be apparent to those skilled in this art without the exercise of inventive facilities.

Accordingly, the specific examples used herein were 15 given for clearness of understanding only and no undue limitations thereon should be implied.

What is claimed is:

1. A refrigerated storage system for the storage of liquid, normally gaseous products, said system comprising:

20 a liquid product storage tank having a liquid product zone and a vapor zone;
means connected to said tank for removing a portion of said liquid product;
25 refrigeration means connected to said liquid product removal means for reducing the temperature of said portion of liquid product;
and a vapor-liquid contactor located above said tank, closed to the ambient atmosphere, and disposed between and in communication with said vapor zone and said refrigeration means for bringing said refrigerated portion of liquid product into intimate contact with vapor withdrawn from said vapor zone into said contactor, said contactor including:

30 a vertically disposed chamber portion;
an outlet at the top of said chamber for removing accumulated non-condensable vapors;
flow control means on said outlet;

35 pipe means for conducting vapor from said vapor zone in said tank, said pipe means having a vapor withdrawing portion depending from said chamber into said vapor zone and a remaining portion extending upwardly within said chamber, substantially coextensive therewith, and terminating at an upper opening;

40 liquid product inlet means in communication with said refrigeration means for receiving said cooled liquid product portion, said inlet means being located to direct refrigerated liquid downwardly from the top of said chamber portion through said chamber portion;

45 and vapor-liquid baffle means disposed between said upper opening in the vapor conducting pipe means and said liquid product inlet means for providing concurrent contact between said vapor and said liquid at the top of said chamber portion and for preventing entry of liquid into said pipe means.

50 2. In a system in accordance with claim 1 in which the said contactor is mounted directly atop the vessel to which the condensate is to be returned.

55 3. In a system in accordance with claim 1 in which said withdrawing portion of said vapor inlet means includes means extending laterally from said depending portion into said vapor zone for facilitating the withdrawal of vapor from said vapor zone.

60 4. In a system in accordance with claim 2 in which said contactor comprises: a direct contact, cascade condenser having said vapor conducting pipe means depending into said vapor zone and being concentrically mounted within said condenser; said condenser further having a plurality of cascade trays mounted on said pipe means and an alternating plurality of cascade trays mounted on said condenser.

65 5. In a system in accordance with claim 4 in which said direct contact cascade condenser has said pipe means, a condensate outlet, and a vent gas outlet incorporated

in a single pipe nozzle supporting said condenser and communicating with said vapor zone.
